(57) **CLAIM**

The ornamental design for a dart projectile, as shown and described.

DESCRIPTION

FIG. 1 is a front perspective view of the dart projectile of the instant invention;

FIG. 2 is a rear perspective view of the dart projectile of the instant invention;

FIG. 3 is a right side elevational view thereof;

FIG. 4 is a left side elevational view thereof;

FIG. 5 is a front view thereof;

FIG. 6 is a rear view thereof;

FIG. 7 is a top view thereof; and,

FIG. 8 is a bottom view thereof.

The broken lines shown are included for the purpose of illustrating the unclaimed portions of the article and form no part of the claimed design.

1 Claim, 2 Drawing Sheets
